US00D775479S

(12) United States Design Patent (10) Patent No.: US D775,479 S
(45) Date of Patent: * Jan. 3, 2017

(54) CHAISE LOUNGE

(71) Applicant: Marijn Aart Willem Oomen,
Ophemert (NL)

(72) Inventor: Marijn Aart Willem Oomen,
Ophemert (NL)

(73) Assignee: Fatboy the Original B.V., 's
-Hertogenbosch (NL)

() Term: 15 Years

(21) Appl. No.: 29/567,512

(22) Filed: Jun. 9, 2016

Related U.S. Application Data

(63) Continuation of application No. 29/534,179, filed on
Jul. 27, 2015, now Pat. No. Des. 764,823.

(30) Foreign Application Priority Data

Jan. 28, 2015 (EM) 002621904

(51) LOC (10) Cl. 06-01

(52) U.S. Cl.

USPC D6/361; D6/377

(58) Field of Classification Search

USPC D6/334-336, 361, 371-373, 375, 377,
D6/381, 716, 716.1, 716.4; D21/803

Esq.; Fross Zelnick Lehrman & Zissu P.C.

(57) CLAIM

The ornamental design for a chaise lounge, as shown and described.

DESCRIPTION

FIG. 1 shows a top view of the chaise lounge;
FIG. 2 shows a bottom view of the chaise lounge;
FIG. 3 shows a head end view of the chaise lounge;
FIG. 4 shows a foot end view of the chaise lounge;
FIG. 5 shows a right perspective side view of the chaise
lounge;
FIG. 6 shows a left perspective side view of the chaise
lounge;
FIG. 7 shows a top perspective view of the chaise lounge;
and,
FIG. 8 shows a detail of the right side foot end of the chaise
lounge.
The broken line showing of the crease lines, buckle, and straps show unclaimed subject matter for the design.

1 Claim, 4 Drawing Sheets
